UNITED STATES PATENT OFFICE.

GEORGE E. PICKUP, OF NEWARK, OHIO, ASSIGNOR TO THE WEHRLE COMPANY, OF NEWARK, OHIO, A CORPORATION OF OHIO.

DESIGN FOR A FRAME FOR GAS-PLATES.

47,197.

Specification for Design.

Patented Apr. 6, 1915.

Application filed December 28, 1914. Serial No. 879,403. Term of patent 3½ years.

To all whom it may concern:

Be it known that I, GEORGE E. PICKUP, a citizen of the United States, residing at Newark, in the county of Licking and State of Ohio, have invented a new, original, and ornamental Design for the Frames of Gas-Plates, of which the following is a specification, reference being had to the accompanying drawing, forming a part thereof.

Figures 1, 2 and 3 are plan, front, and

end views, respectively, of the frame of a gas plate embodying my new design.

I claim:

The ornamental design for the frame of a gas plate, as shown.

GEORGE E. PICKUP.
